UNITED STATES PATENT OFFICE.

FRANK YOKEL, OF CLEVELAND, OHIO, ASSIGNOR, BY MESNE ASSIGNMENTS, TO MARKEL ELECTRIC PRODUCTS, INC., OF BUFFALO, NEW YORK, A CORPORATION OF NEW YORK.

DESIGN FOR A HEATING UNIT FOR ELECTRIC HEATERS.

Application filed January 12, 1927. Serial No. 20,339. Term of patent 3½ years.

To all whom it may concern:

Be it known that I, FRANK YOKEL, a citizen of the United States, residing at Cleveland, in the county of Cuyahoga and State of Ohio, have invented a new, original, and ornamental Design for a Heating Unit for Electric Heaters, of which the following is a specification, reference being had to the accompanying drawing, forming part thereof.

In said drawing:

The figure is a perspective view of a unit embodying my new design.

I claim:

The ornamental design for a heating unit for electric heaters, as shown.

FRANK YOKEL.
